UNITED STATES PATENT OFFICE.

BENJAMIN WORTHINGTON, OF MOZART, PENNSYLVANIA.

SANITARY APPLIANCE.

1,017,940.

Specification of Letters Patent. Patented Feb. 20, 1912.

Application filed March 15, 1911. Serial No. 614,574.

To all whom it may concern:

Be it known that I, BENJAMIN WORTHINGTON, a citizen of the United States, residing at Mozart, in the county of Bucks and State of Pennsylvania, have invented certain new and useful Improvements in Sanitary Appliances, of which the following is a specification.

My invention relates to sanitary appliances, and more particularly to improved means for dispensing sanitary water closet covers, which may be effectually operated in connection with a coin controlled mechanism, and adapted to be placed in public 15 toilets and the like.

A further object is to provide an improved apparatus of this character which when operated, will feed a strip of folded paper and will cut the folded paper so that 20 it may be used for the purposes intended.

With these and other objects in view, the invention consists in certain novel features of construction and combinations and arrangements of parts, as will be more fully 25 hereinafter described and pointed out in the claim.

In the accompanying drawings: Figure 1, is a view in vertical section illustrating my improvements. Fig. 2, is a plan view showing the casing or box in section. Fig. 3, is a view in vertical section through the casing, showing the operating mechanism in elevation. Fig. 4, is a fragmentary view in elevation of the cutting roll. Fig. 5, is a broken 35 sectional view, illustrating the meeting surfaces of the two rolls, and showing the groove in one roll to receive the cutter on the other. Fig. 6, is a view of the cut blank, and Fig. 7, is a view of the blank unfolded, ready for use.

1, represents a box or casing preferably having a removable top 2 secured from the inside by screws 3, and provided with a hinged bottom 4, which may be locked in 5 various ways, a lock 5 being shown for the purpose.

Inside of casing 1, U-shaped bearings 6 are provided for a shaft 7, on which a transversely disposed roller 8 is secured. This 3 roller 8 cooperates with a similar roller 9 below. The shaft 10 of roller 9 is mounted in blocks 11, which are adjustable in guides 12 by means of screws 13, so as to adjust the roller 9 toward roller 8, and regulate the pressure on a strip of paper 14, which is wound off of a roll 15. This roll 15 is mount-

ed on a spool 16, and the latter is supported to turn in bearing 17 in the casing. On shaft 7, a gear wheel 18 is secured, and meshes with a gear wheel 19 on an operating 60 shaft 20 which, at one end, projects through casing 1, and is provided with a crank arm 21 to turn the same. This shaft 20 is mounted in adjustable bearings 22, and is provided with suitable coin controlled mechanism to 65 regulate the operation of the shaft. The invention, of course, is not limited to any particular coin controlled mechanism, but for purposes of illustration, I have shown a coin guide 23, which directs the coin into contact 70 with a lever 24, and the latter has a hooked end engaging in a notch 25, in a disk 26 on shaft 20, so that in order to turn the shaft a complete revolution, it is necessary to drop the proper coin into the casing. 75

The paper 14 above referred to, is folded longitudinally, and feeds between the rolls 8 and 9, and over a platform 27, and through a slot 28, one wall of said slot constituting a straight edge against which the paper is 80 torn.

On roller 8, a knife 29 is secured, and is of the peculiar shape shown most clearly in Fig. 4, so as to form a cut in the paper such as shown in Fig. 6. That is, this cutter 85 forms a cut in the paper from the folded edge of the paper inward in a curved line, and then cuts longitudinally of the paper. To receive the knife 29, roll 9 is made with a correspondingly shaped groove 30, so as 90 to allow the knife to cut clear through the paper, and to more effectually guide the paper, roller 9 is provided at its ends with annular flanges 31.

In operation, when shaft 20 is released by 95 the insertion of the proper coin, said shaft is given a complete revolution, and the coin controlled means then again locks the shaft. During this complete revolution of shaft 20, gear 19 turns gear 18 and shaft 7. This 100 causes rollers 8 and 9 to turn, feeding the folded paper through the slot 28, at the same time making the cut in the paper as above explained. When the paper is fed out as far as it will go, it is then torn off 105 against the straight edge formed by one wall of slot 28, and is ready for use. That is, the paper is opened out as shown in Fig. 7, and the tongue which forms the opening 32, is bent downward and fits against the 110 forward portion of the seat. Suitable means will, of course, be provided in the

2
casing for the reception of coins or checks. I have shown a simple mechanism for caring for the coins, by providing a raised tongue 33 on the bottom 4, to prevent the coins from 5 falling onto the floor when the bottom is opened.

Various slight changes might be made in the general form and arrangement of parts described without departing from my invention, and hence I do not limit myself to 10 the precise details set forth, but consider myself at liberty to make such changes and alterations as fairly fall within the spirit and scope of the appended claim.

15 Having thus described my invention, what I claim as new and desire to secure by Letters Patent is:

A device of the class described, compris-

ing two parallel contacting rolls, a cutter blade projecting from the periphery of one 20 of said rolls, said blade extending inwardly a distance from one end of the roll and then circumferentially around the roll for a fixed distance, the other roll being provided with corresponding groove, a reel, a casing confining said rolls and said reel and provided 25 with a slot adjacent said rolls, one edge of said slot being formed with a cutting edge, substantially as described.

In testimony whereof I have signed my 30 name to this specification in the presence of two subscribing witnesses.

BENJAMIN WORTHINGTON.
